UNITED STATES PATENT OFFICE.

PETER BROWN, OF CHICAGO, ILLINOIS, ASSIGNOR TO O-CEDAR CORP'N, A CORPORATION OF ILLINOIS.

CARTON AND METHOD OF WRAPPING MOPS.

Application filed July 29, 1926. Serial No. 125,625.

This invention relates to cartons for implements and more particularly to cartons adapted to enclose a mop or a portion thereof so as to protect the same from exposure and injury.

Such an arrangement prevents the strands of the mop fabric from becoming tangled with other objects and avoids the possibility of oil or the like which is frequently on mop fabrics, from staining objects with which it might come in contact. Further, it eliminates the danger from spontaneous combustion as well as retains the mop clean and free from dust and other foreign substances.

Cartons heretofore used for the above mentioned purpose have not proven entirely satisfactory, they being usually in the form of boxes or cans which are more or less expensive, bulky, and necessitate that the mop head to be encased therein be detached from the handle. Moreover, devices of known construction, are not adapted for display purposes, and as a consequence thereof fail to serve an important commercial purpose.

It is accordingly an object of this invention, to provide a carton which is light, compact, and of simple construction.

Another object is to provide a carton which obviates the necessity of detaching the mop head from the handle, and which is adapted for display purposes.

Other objects and advantages will appear from the following description of an illustrated embodiment of the present invention.

In the drawings:

Figure 1 is a detail side view in elevation of a mop head encased in a carton embodying features of the present invention.

Figure 2 is a fragmentary sectional view in elevation.

Figure 3 is a plan view of the structure shown in Figure 1.

Figure 4 is a reduced development of the carton shown in Figure 3.

The structure selected for illustration comprises a mop supporting member 1 adapted to retain a mop fabric 2 therein. The supporting member 1 is, in this instance, of the transversely extending type, but it may be of any form without departing from the spirit of this invention. A handle socket 3 is secured in any suitable manner to the top of the supporting member 1 and is secured to the latter by means of a flat connecting portion 4, thereby leaving a recess between the

supporting member 1 and the handle socket 3. The lower side of the socket 3 provides a shoulder 5 for a purpose that will be apparent hereinafter.

A carton illustrative of the present invention comprises a substantially rectangular sheet 6 composed preferably of any suitable sheet material, which is provided with apertures 7 and 8 adjacent its respective ends along a median line thereof. Each of the apertures has a portion of an edge thereof semi-circular in form, the remainder being slightly curved but comparatively straight. The slightly curved portion is disposed adjacent the respective ends of the sheet 6 as will be apparent from the showing in Figure 4. The sheet 6 is adapted to be wrapped about the mop head to substantially enclose the same, the socket 3 of the mop extending through each of the apertures 7 and 8 with the ends of the sheet overlapping each other to bring the apertures in alignment. The sheet 6 will normally tend to assume its extended position, thereby causing the comparatively straight portion of the edge of the aperture 8 to engage the shoulder 5, thus holding the sheet against working off the mop head. The comparatively straight portions of the edges of the apertures will abut opposite sides of the flat portion 4 so as to effect a snug fit. As shown in Fig. 3, the carton may be descriptively marked along the length thereof for display purposes.

It will be obvious to those skilled in the art that the foregoing carton may be used not only for protecting mop heads but in connection with any implement which has a head and a handle socket thereon without departing from the spirit of this invention.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. The combination with an implement having a head and a handle socket thereon, said handle socket having a shoulder thereon, of a sheet having an aperture adjacent each end thereof, said sheet being adapted to be wrapped about said head with its ends overlapping and positioned over said socket, the latter extending through said apertures

with the outer overlapped end in locking engagement with said shoulder.

2. The combination with an implement having a head and a handle socket thereon, said socket having a shoulder thereon, of a substantially cylindrical carton for said head, said carton having an aperture in the side thereof for receiving said socket therethrough, the edge of said aperture being 10 adapted to co-act with said shoulder for holding said head in position in said carton.

3. The combination with an implement having a head and a handle socket thereon, said socket having a flat portion thereon, of

a sheet having an aperture adjacent each end thereof, said apertures each having a portion of the edge thereof comparatively straight, said sheet being adapted to be wrapped about said head with its ends overlapping and positioned over said socket, the latter extending in said apertures with the comparatively straight portions of the edges of said apertures in abutting engagement on opposite sides of said flat portion. 15

20 In testimony whereof I have hereunto subscribed my name.

PETER BROWN.
